SAMUEL E. SPERRY, OF WOODHAVEN, NEW YORK, ASSIGNOR TO INTERNATIONAL TYPESETTING MACHINE COMPANY, OF NEW YORK, N. Y., A CORPORATION OF NEW YORK.

MAGAZINE-ENTRANCE GUIDE FOR LINE-COMPOSING MACHINES.

1,130,641.

Specification of Letters Patent.

Patented Mar. 2, 1915.

Application filed April 23, 1913. Serial No. 763,140.

To all whom it may concern:

Be it known that I, SAMUEL E. SPERRY, a citizen of the United States, residing at Woodhaven, in the county of Queens and State of New York, have invented new and useful Improvements in Magazine-Entrance Guide for Line-Composing Machines, of which the following is a specification.

The present invention relates to improvements in line composing and type casting machines and more particularly to those of the well-known linotype class wherein the matrices are returned to the magazine after the casting operation, and the primary object of the invention is to provide an improved guide for directing the matrices from the distributor into the matrix-receiving channels of the magazine. Heretofore, in machines of this class, it has been customary to employ a guide between the distributor and the magazine, but in those cases the guide terminated at the matrix-receiving end of the magazine, and experience has demonstrated that the guide in such cases became displaced relatively to the magazine, causing lack of registration between the matrix passages of the guide and the matrix channels of the magazine, with the result that the matrices frequently tilted to such extent as to clog or obstruct the matrix-receiving end of the magazine, necessitating stopping the machine and removing the obstruction.

According to the present invention, the matrix guide projects into or lies partly within the matrix-receiving end of the magazine, thereby insuring correct entrance of the matrices into the magazine and avoiding the objections heretofore experienced.

To this end, the invention consists in certain improvements, and combinations and arrangements of parts, all as will be herein-after more fully described, the novel features being pointed out particularly in the claims at the end of the specification.

In the accompanying drawing: Figure 1 represents a vertical section of the upper end of the magazine, the distributor, and the matrix guide interposed between the magazine and distributor, the guide embodying the present invention; Fig. 2 shows portions of the magazine and the guide in co-operative relation and illustrates diagrammatically the manner in which the matrix is di-

rected by the guide into the magazine; Figs. 3 and 4 show, in edge view and side view, respectively, one of the matrix-guiding partitions as shown in Figs. 1 and 2; Figs. 5 and 6 are similar views showing another form of matrix-guiding partition adapted to be used according to the present invention; Figs. 7 and 8 are detail views showing another form of matrix-guiding partition embodying the present invention, these latter figures illustrating the manner in which partitions of this kind coöperate with the magazine; Fig. 9 represents a transverse section on the line 9—9 of Fig. 7.

Similar parts are designated by the same reference characters in the several views.

Matrix guides embodying the present invention are capable of use in connection with line composing machines of various types wherein the matrices, after use, are returned to the magazine. In the present instance, different embodiments of the invention are shown in connection with a machine of the well-known linotype class, but it will be understood that the invention is not restricted to the particular constructions shown, as equivalent constructions may be used within the scope of the claims at the end of the specification.

The matrix guide forming the subject matter of the present invention is interposed between the matrix distributor and the upper or matrix-receiving end of the magazine and serves to receive the matrices from the distributor and to direct them into the appropriate channels of the magazine. The distributor, as shown, embodies a distributor bar 1, the lower edge of which is provided with ribs to coöperate with the teeth formed in the tops of the matrices M, and revoluble screws 2 coöperate with the matrices to feed them along the distributor bar while the matrices are suspended therefrom owing to the engagement of the teeth of the matrices with the ribs on the distributor bar, these ribs being so arranged with respect to the projections on the matrices as to cause the matrices to drop from the distributor bar when the matrices occupy positions above the respective channels of the magazine, all of which will be readily understood by those skilled in the art. The magazine embodies top and bottom plates 3 and 4 which are formed with pairs of complementary grooves

providing channels 5 and 6 which receive the lugs of the matrices. The magazine is inclined in order that the matrices will gravitate from the upper receiving end toward the lower or delivery end, as usual, and in order to facilitate entrance of the matrices into the respective channels, the walls at one side of the channels are preferably beveled, as at 7.

10 The guide which receives the matrices from the distributer and directs them into the appropriate channels of the magazine embodies a curved plate 8 which extends from a point beneath the distributer bar to the upper end of the magazine, and a set of upright or vertically arranged partitions 9, the curved plate 8 supporting the matrices as they drop from the distributer bar and pass into the magazine, and the partitions 9 guiding the matrices so that they shall move in an edgewise direction. According to the present invention, these matrix-guiding partitions 9 extend downwardly and forwardly past the upper end of the magazine and 25 project into the matrix-receiving end of the magazine, thereby preventing lodgment of the matrices upon the upper end of the magazine or tilting of the matrices to such extent as to bind and thereby prevent their entrance into the magazine. These matrix-guiding partitions are, in the present instance, connected and maintained in proper relation by a tie bar 10 and they are provided with lugs 11 adapted to coöperate 35 with retaining projections 12, the latter being formed on a carrier frame 13 which is adapted to swing to and from operative position about a pivot 14.

The matrix-guiding partitions may be 40 constructed in different ways. In Figs. 1-4 inclusive, each partition is composed of a pair of plates 15 and 16 secured together flatwise and having their lower ends 17 and 18 spread apart, these ends of the partition 45 projecting into the magazine and lying between the top and bottom plates thereof, as shown in Figs. 1 and 2.

In Figs. 5 and 6, another form of partition is shown which is composed of a single 50 plate having its lower end cut at 19 and 20 to form a central portion 21 and a pair of upper and lower portions 22 and 23, the central portion 21 in this instance being in alignment with the remainder of the partition 55 while the portions 22 and 23 are bent or deflected laterally as shown in Fig. 5.

In Figs. 7, 8 and 9, the partition 24 is composed of a plate the lower end of which projects into the upper or matrix-receiving end of the magazine as in the previously described constructions, but this portion of the partition is formed with corrugations 25 which render the lower end of the partition rigid. The lower corrugated end of the 65 partition projects into the upper end of the

magazine and lies in a plane between the ribs which separate the adjacent matrix-receiving channels, as shown in Fig. 8.

In each of the constructions shown, the upper and lower edges of each guiding partition are cut away, thereby reducing that portion of the partition which projects into the magazine. These portions of the partitions which project into the magazine lie preferably in planes between the ribs which 75 separate the matrix channels in the magazine, and the matrices as they enter the magazine pass between these partitions and are guided thereby in a manner which prevents obstruction, either by angular deflection, or 80 lodging of the matrix against obstructing surfaces or projections.

I claim as my invention:—

1. In a machine of the linotype class, in combination, the matrix-containing magazine, the distributing mechanism, and means for guiding matrices from the distributing mechanism to the magazine, said means having laterally widened guiding parts projecting into but unattached to the magazine. 85

2. In a machine of the linotype class, a channeled matrix magazine, and means for guiding matrices thereto, said means having laterally widened portions within the magazine and occupying positions between but 95 unattached to the top and bottom plates of the magazine.

3. In a machine of the class described, the combination of a matrix-containing magazine, a matrix distributer, and guiding means arranged to receive matrices from the distributer and to direct them into the magazine, portions of said guiding means being laterally widened and projecting into the magazine and being positioned freely 100 between the top and bottom plates thereof.

4. In a machine of the class described, the combination of a magazine having channels to receive matrices, a distributer, and guiding means arranged to receive matrices from the distributer and to direct them into the appropriate channels of the magazine, portions of said guiding means being laterally widened and projecting into the magazine 110 at points between adjacent channels therein 115 and being positioned freely between the top and bottom plates of the magazine.

5. In a machine of the class described, the combination of a magazine having matrix-receiving channels, a matrix distributer, and 120 guiding means arranged to receive matrices from the distributer and to direct them into the different magazine channels, said guiding means having rigid laterally widened portions projecting into but unattached to 125 the matrix-receiving end of the magazine and lying in planes wholly between the top and bottom plates thereof.

6. In a machine of the class described, the combination of a magazine having top and 130

bottom plates formed with opposed pairs of matrix-receiving channels, a matrix distributor, and guiding means between the distributor and magazine embodying laterally spaced partitions having their ends widened laterally and projecting into the magazines and unattached to and lying in planes between the top and bottom plates.

7. In a machine of the class described, the combination of a magazine having matrix-receiving channels, a matrix distributor, and means for guiding matrices from the dis-

tributer to the magazine, said means embodying laterally spaced partitions having corrugated portions which project into and 15 are unattached to the magazine.

In testimony whereof I have hereunto set my hand in presence of two subscribing witnesses.

SAMUEL E. SPERRY.
